UNITED STATES PATENT OFFICE.

ALBERT L. HIGGINS, OF BAR HARBOR, MAINE.

DRAG TOY.

Application filed May 7, 1926. Serial No. 107,397.

This invention relates to a toy for use by small children, the same being of that type adapted to be drawn over the ground by means of a cord, one of the objects being 5 to simplify and correspondingly reduce the cost of the toy while retaining many of the attractive features of a toy wherein relatively movable parts are provided.

A further object is to provide a toy of 10 this character which simulates a duck or other fowl, an animal, or other objects such as a canoe, a boat, etc., each having a relatively movable part.

With the foregoing and other objects in 15 view which will appear as the description proceeds, the invention resides in the combination and arrangement of parts and in the details of construction hereinafter described and claimed, it being understood that 20 changes in the precise embodiment of the invention herein disclosed may be made within the scope of what is claimed, without departing from the spirit of the invention.

In the accompanying drawings the pre- 25 fered form of the invention has been shown.

In said drawings,

Figure 1 is a side elevation of the toy, the base being shown in section.

Figure 2 is a top plan view.

30 Figure 3 is a section on line 3—3 Figure 1.

Figure 4 is a section on line 4—4 Figure 1.

Figure 5 is a side elevation of a modified 35 form of toy.

Figure 6 is a top plan view thereof.

Figure 7 is a bottom plan view.

Figure 8 is a section on line 8—8, Figure 5.

Referring to the figures by characters of 40 reference 1 designates a base adapted to rest on and to be pulled along the surface of the ground, this base being provided with a longitudinal slot 2 bridged by the intermediate portion of a staple 3 the ends of which are seated in the base.

45 Pivotaly mounted on the staple 3 is the body portion 4 of the toy which can be cut out to simulate a duck or other fowl or animal, there being a recess 5 in the back portion of the bottom of this body. Jour- 50 naled in this recess is an eccentric ground engaging wheels 6 held in place preferably by a transverse pin 7. The body has a forwardly extending crop 8 adjacent the top surface of the base 1 and extending up- 55 wardly within the body through the crop is a bore 9 the upper end of which opens

into a transverse opening 10. Eyes 11 in the form of disks of any suitable contour are located adjacent the ends of the opening 10 and are connected by a cross pin 12 from 60 which projects a stem 13. This stem is adapted to work freely within the bore 9 and has its lower end mounted loosely on the base 1.

It will be apparent that when the top 65 is pulled forwardly the wheel 6 will rotate and cause the body 4 to oscillate upon its bearing 3. At the same time the crop 8 will move toward and from the base 1 and as the stem 13 and the eyes 11 do not move 70 with the body but are supported by the base it will be obvious that a relative movement of the body and eyes will thus be set up.

In Figures 5 to 8 inclusive a slightly modified form of toy has been illustrated. In 75 this form of the device the movable eyes have been eliminated and instead of painting the wings directly on the body, they have been applied thereto. Referring specifically to these figures the base has been 80 indicated at 14 and has a slot 15 the ends of which diverge upwardly. The lower portion of the body 16 is mounted in the slot 15 and is tiltably supported by a transverse pin 17 extending through the base and across the 85 slot. This body has a recess 18 in its bottom face in which an eccentric wheel 19 is mounted to rotate freely. Relatively thin strips of material cut to simulate wings and indicated at 20 are applied in any suitable manner to the sides of the body 16. 90

The parts are so proportioned that when the toy is drawn forwardly the eccentric wheel 19 will revolve and cause the body 16 to tilt forwardly and backwardly. During this operation the front portion of the body will strike against the front inclined wall of the slot 15 and produce a quacking sound. At the same time the impact of the body against this front wall of the slot 100 will cause the face 14 to swing slightly upwardly at the back. Thus as the rear portion of the body descends immediately following its forward tilting, the lower edges of the wings 20 will strike upon the base and 105 produce another quacking sound. Consequently the forward movement of the toy will set up a sound simulating that of the quack of a duck.

It might be stated with reference to the 110 structures shown in Figures 1 to 4 inclusive that a sound is also produced in a somewhat

similar manner by the tilting of the body relative to the base during the forward movement of the toy, this sound being caused by the impact of the relatively movable parts against each other.

5 While a figure of a duck has been illustrated in the drawings it is to be understood that simulations of other fowls or animals can be used and the parts be caused to operate in the same manner heretofore described.

10 What is claimed is:

A drag toy including a base for sliding

engagement with a supporting surface, said base having a slot, a body pivotally mounted 15 relative to the base and projecting into and above the slot, and an eccentric ground engaging wheel connected to the body, said wheel constituting means for tilting the body back and forth into contact with the 20 base during the forward movement of the body, thereby to produce a noise.

In testimony that I claim the foregoing as my own, I have hereto affixed my signature.

ALBERT L. HIGGINS.
